UNITED STATES PATENT OFFICE.

BENJAMIN FRANKLIN FINDLEY, OF DENVER, MISSOURI.

ROAD-DRAG.

1,224,728.

Specification of Letters Patent.

Patented May 1, 1917.

Application filed December 20, 1916. Serial No. 138,039.

To all whom it may concern:

Be it known that I, BENJAMIN FRANKLIN FINDLEY, a citizen of the United States, residing at Denver, in the county of Worth and State of Missouri, have invented new and useful Improvements in Road-Drags, of which the following is a specification.

This invention is an improved road drag for scraping and leveling roads, the object of the invention being to provide an improved machine of this character which embodies means to adjust the blade at any desired angle to the line or draft and which also embodies means to permit the tilting of the blade to prevent injury thereto by stumps, stones, or the like and which further embodies means to raise and lower the blade and the front end of the drag and to permit the drag, when not in use to be readily moved from place to place.

The invention consists in the features of construction, combination, and arrangement of devices, hereinafter fully described and claimed.

25 In the accompanying drawings:—

Figure 1 is a plan of a road drag constructed and arranged in accordance with my invention.

Fig. 2 is an elevation of the same partly 30 in section.

Figs. 3 and 4 are detail sectional views of the same respectively on the planes indicated by the lines 3—3 and 4—4 of Fig. 1.

The blade 1 is provided with rounded 35 lower corners 2 and is provided at its center at its upper side with a connecting element 3 having an eye which eye is engaged by the eye 5 of a similar connecting element 6 secured under the front end of the reach 7, 40 hence the blade is connected to the front end of the reach for universal angular movement, so that the blade may be arranged in vertical or in inclined position and may be also arranged at any desired angle 45 with respect to the reach and the line of draft. A segment link 8 is slidably arranged on the reach and in a guide 9 and is provided with a series of adjusting openings 10, any one of which may be engaged 50 by a securing pin 11. The ends of the segment link are connected to the blade by hinges 12. Hence the blade may be arranged and secured at any desired angle with respect to the line of draft.

55 The blade is provided at a point near its

center with an upwardly extending tilting lever 13. A cross lever 14 is fulcrumed on the reach, as at 15 and has its shorter end connected to the lever 13 by a link rod 16, said link rod engages a clip 17, which passes 60 around the lever 13, the said clip being adjustable on the lever 13 and being held between a pair of collars 18, the said collars being adjustably secured by set screws 19. An angle lever 20 is also fulcrumed on the 65 reach as at 21 and has arms 22, 23, the latter extending outwardly to one side of the reach. The arm 22 of the angle lever is connected by a pair of links 24 to the longer arm of the lever 14. A coiled retractile spring 25 has one end secured to the reach as at 26 and has the other end connected as at 27 to the arm 23 of the angle lever.

It will be observed and understood that 75 the levers 13, 14, 20 and their connections, normally hold the blade in the required upright position for operation, but permit the blade to turn rearwardly to an inclined position and to pass over stones, stumps, or 80 the like, and thus avoid being injured, the spring 25 in connection with said levers then restoring the blade to its initial operative position.

An axle 28 is secured near the rear end 85 of the reach and extends from opposite sides thereof. A pair of disks 29 are mounted on the ends of the axle and are provided with boxings 30 on opposite sides.

These disks serve to prevent the drag 90 from moving sidewise and serve to relieve side draft. Fenders 31 are provided for the disks.

I also provide an axle 32 for the front portion of the drag, said axle having supporting wheels 33 mounted thereon and being provided with an arched or crank portion 34 which is pivotally mounted in bearings 35 on the under side of the reach at a point a suitable distance from the front end 100 of the latter. The arch axle has an upwardly extending lever 36. A hand lever 37 is pivotally mounted at its lower end as at 38 on a segment 39 which is secured to one side of the reach at a suitable point and said hand lever has a dog 40 of usual construction to coact with the teeth of the segment and secure said lever in any desired adjusted position. A link rod 41 is connected to the upper end of the lever 36 and 110

passes through and is slidably engaged in a guide 42 which is secured on the hand lever. A spring 43 is arranged on the rear portion of the link rod and bears between an adjusting nut 44 and the said guide so that said spring coacts with the levers and link rod to yieldably hold the front arched axle in any desired adjusted position. A stop 45 is provided on the link rod to limit the longitudinal movement thereof. It will be understood that when the hand lever is operated, the axle 32 may be raised or lowered as required to lower or raise the front end of the drag and the blade and hence the blade may be caused to operate at any desired depth and may be also raised completely out of engagement with the surface of the road to permit the drag to be readily transported from point to point.

20 A channel iron 46 is secured on the rear and is provided with a series of adjusting openings 47. The seat 48 has a standard 49 which may be secured by bolts 50 at any desired longitudinal adjustment, the said bolts engaging certain of the openings in the iron 47.

Copies of this patent may be obtained for five cents each, by addressing the "Commissioner of Patents, Washington, D. C."

Having described the invention, what is claimed is:

1. In a drag, a supporting element, a blade connected to the supporting element 30 for universal angular movement and provided near its center with an upstanding lever, a cross lever mounted on said supporting element, a connection between one end of the cross lever and the lever of the blade, 35 and a connecting means, including a cushioning spring between the other end of the cross lever and the supporting lever.
2. In a drag, a supporting element, a blade connected to the supporting element 40 for vertical angular movement and provided with a lever, a cross lever mounted on said supporting element, connecting means between one end of the cross lever and the lever of the blade, an angular lever mounted 45 on said supporting element, a link connecting one arm of the angle lever to the cross lever and a cushioning spring attached to the other arm of the angle lever and also attached to the supporting element.

In testimony whereof I affix my signature.
BEN. FINDLEY.
